UNITED STATES PATENT OFFICE.

ANTONINO MAURO, FILIPPO MAURO, AND BENEDETTO MAURO, OF NEW YORK, N. Y.

PIANO WITH TRANSPOSING-KEYBOARD.

1,071,767.

Specification of Letters Patent.

Patented Sept. 2, 1913.

Application filed February 20, 1912. Serial No. 678,971.

To all whom it may concern:

Be it known that we, ANTONINO MAURO, FILIPPO MAURO, and BENEDETTO MAURO, subjects of the King of Italy, residing in the 5 borough of Manhattan, in the city, county, and State of New York, have invented certain new and useful Improvements in Pianos With Transposing-Keyboards, of which the following is a full, clear, and exact 10 description, reference being had to the accompanying drawings, forming a part of this specification.

Our invention relates to certain new and useful improvements in movable keyboards 15 for pianos and organs, and its primary object is to provide a transposing keyboard which can be used in connection with pianos in which the hammers are not arranged at a uniform distance.

20 A further object is to provide a transposing keyboard for pianos and organs, capable of being applied to existing instruments having the hammers unevenly distributed, requiring only a few slight changes 25 which can be readily made without the necessity of any special skill.

A still further object is to provide a transposing keyboard for pianos and organs simple and inexpensive in its construction and 30 application, and in which especial attention has been given to the ease and convenience in operation.

The object of devices of this class is to 35 enable the operator to produce music in a higher or in a lower key than that in which the music is written. Such transpositions of key are very often required in connection with accompaniment to singing, and to obtain the same with the usual keyboard, either 40 requires a special ability on the part of the player, or else requires costly and long work of rewriting the music in the key desired. Transposing keyboards to facilitate this work have been heretofore made, but to our 45 knowledge, none of these have been commercially successful on account especially of the many operations which they require in order to effect an adjustment of the keyboard. Moreover, such keyboards as have 50 been made were only capable of application to pianos having the hammers evenly distributed, or in other words, to pianos having vertical strings; while the majority of pianos are made with the so-called diagonal 55 strings and built with three separate sec-

tions of piano actions separated by empty spaces, which are usually utilized for the mounting of brackets, sustaining the action rail. In addition to this, it may be remarked that the adjustable keyboards which 60 to our knowledge, have been heretofore made, either require a special form of construction of piano, or else require considerable changes in the same, entailing expense and necessitating the sending of the piano 65 to the factory for being put in order. We have sought to remedy all these inconveniences by producing a keyboard such as represented in the drawings, in which—

Figure 1 is a plan view of the keyboard in 70 its normal position; Fig. 2 is a front view of the same in its normal position; Fig. 3 is a front view of the keyboard released from its operating position and ready to be transposed; Fig. 4 is a front view of the 75 same, transposed three keys to the right and clamped in position; Fig. 5 is a sectional side view in elevation of the keyboard as represented in Fig. 2; Fig. 6 is a sectional side view in elevation of the keyboard in 80 its released position as represented in Fig. 3; Fig. 7 is a detail front view in elevation illustrating a form of screw clamps which 85 may be used in connection with our device; Fig. 8 is a detail front view in elevation showing the arrangement of the hammers usually found in pianos having diagonal strings and the arrangement of the actuating rod for the same modified according to 90 our invention; Fig. 9 is a detail plan view showing an arrangement of our upper equalizing devices; Fig. 10 is a detail sectional plan view through line A—A of Fig. 8, showing an arrangement of the lower equalizing devices; Fig. 11 is a perspective view 95 showing in detail our equalizing devices as applied to a single key and respective hammers; Fig. 12 is a detail front view in elevation of a simple form of equalizing devices and Fig. 13 is a detail plan view of the 100 same; Fig. 14 is a detail side sectional view in elevation, illustrating a preferred form of clamping and operating device; and Fig. 15 is a detail front view in elevation of the 105 same.

Referring to Figs. 1 to 6, 20 designates the front part of a piano frame having a bottom 21. Within said frame is pivotally and shiftably mounted the keyboard frame 22 in such a manner that its rear part has a 110

tendency to tilt down on account of its weight or on account of the difference of leverage between the rear and the front part of said keyboard frame. To allow said 5 tilting of the keyboard frame, bottom 21 is sloped down at its rear part at 23. The tendency of the keyboard frame to tilt down at the rear end can be obtained in many different ways, in the simple manner 10 shown in the drawings, by arranging the pivots for the same toward its front end so as to produce a longer leverage for its rear end. Said keyboard frame can be mounted in any suitable manner so as to be pivotally 15 and shiftably movable; one simple way is shown in the drawings, in which said keyboard frame is provided at each end with a plate 24, 25, projecting underneath said frame, and through which we insert pivots 26, 27, fixed to part 21 in 28, 29. A construction whereby the transposing keyboard has a tendency to tilt down at its rear end constitutes an improvement over the construction usually employed, inasmuch as 25 the rear ends of the keys automatically clear the actuating rods, and the keyboard can be freely shifted without the necessity of the operator lifting its weight. It is obvious that by this construction the operation of this device is rendered easier 30 and quicker and one of the objections to its practical success is overcome.

As it is clearly shown in the drawings, Fig. 1, keyboard frame 22 is shorter than 35 the inside space of the piano frame and therefore can be shifted to the right or to the left within the same, plates 24, 25, sliding on pivots 26, 27. 30 are a plurality of keys mounted on said keyboard frame in 40 the usual manner, the rear end of which normally corresponds with the rods 31 actuating the hammers. In pianos where rods 31 are evenly distributed, all that is necessary to do in order to effect the transposition 45 of the keyboard is to tilt the same so as to lower its rear part, thus freeing the end of levers 30 from the lower end of rods 31 and rendering the keyboard frame free to be shifted to the position desired, 50 where it can be fixed in the operative position in relation to rods 31.

In transposing keyboards for pianos and other musical instruments, the shifting and the clamping and releasing of the same are 55 usually obtained by means of separate devices requiring separate operations and different movements in order to accomplish the complete transposition from one position to another. This does necessarily mean 60 a complication in the operation of the device and has proved to be one of the main causes of the general commercial failure with which such devices have heretofore met. We have sought to remedy this inconvenience in a simple and efficient manner by

adopting means for clamping and releasing the keyboard frame which can also at the same time be used for operating the shifting of the same. To this end at the front part of bottom 21, we provide longitudinal slots 32, 33, through which are respectively inserted clamps 34, 35, provided with handles 36, 37, and inserted through keyboard frame 22, each one being provided with a retaining plate 38. As clearly illustrated in 70 Figs. 15 and 16, the lower part of said clamp comprises a cam-acting portion 39 adapted to enter through the respective slots provided in bottom 21 when the clamps are turned 90 degrees to the front from the position shown in said Figs. 15, 16. In said 75 position cam-acting portion 39 rests against the lower surface of bottom 21, clamping keyboard frame 22 in the operating position; the action of the clamping portion 39 is preferably exerted against plates 40, 40', made of metal or other wear resisting material, provided in the lower surface of bottom 21. On operating handles 36, 37, so as to rotate said clamps, the same will therefore cause the forward part 39 of keyboard frame 22 to be clamped to bottom 21 or to be relieved from the same. In Figs. 2 and 5, keyboard frame 22 is shown in the clamped or operating position, and in Figs. 3 and 6, 90 the same is shown in its released position ready for being transposed. The cam-acting clamps just described can also be effectively substituted by screw clamps such as 95 illustrated in Fig. 7. Screw clamps 34' are inserted through the slots 32, 33, and 100 screwed to the bottom of keyboard frame 22, and are provided with a shoulder 38' resting against the lower surface of bottom 21. The same have preferably a long pitch 105 and are mounted in such a manner that when keyboard frame 22 is clamped in position, handles 36', will be turned sidewise and concealed from view. By turning the same 90 degrees to the front, the keyboard frame will be sufficiently released so as to be free to move in either direction and the 110 handles 36' afford a very convenient means to perform said shifting; when the desired position is reached, said handles are turned 115 back and keyboard frame 22 will thus again be clamped in its operating position.

As a guide for the transposition on the front part of the piano and right above the finger keys, we provide a plate 41 bearing 120 the entire octave in half tones; and to insure the exact position of the keyboard frame at all points where the rear ends of keys 30 register with the actuating rods, we provide positioning means for the same 125 which may be constituted by a plate 41' provided with notches 42 fixed on the piano frame by a cog 43 and adapted to engage said notches. We prefer to make said notches with inclined sides, plate 41 having 130

therefore the shape of a rack with pointed teeth; cog 43 on the other hand is also pointed with inclined sides at its projecting end and therefore the combined action of its inclined sides with the inclined sides of notches 42 will be to effect slight motions of the keyboard frame to force the same from the position to which it has been shifted by hand to the exact operating position. In other words the object of notches 42 and cog 43 is to relieve the operator of the excessive attention which would otherwise be needed to set the keyboard frame in the exact position. To further facilitate the shifting motion of keyboard frame 22, we also provide rollers 44 provided at the rear end of part 21 on which said keyboard frame will rest when its rear part is in its lowered position.

The great majority of pianos, as we have hereinbefore stated, are built with the hammers unevenly distributed along the entire length of the piano; and, more particularly, the same are generally arranged in groups, usually three, separated by empty spaces in which are located brackets forming part of the skeleton of the instrument. We have found that the part of said brackets below the level of the piano actions proper, can be removed without impairing the strength or the stability or the other qualities of the instrument.

In Fig. 8, we show in elevation the general arrangement of wippens 45, actuating rods 49 for the same, and rear ends of keys 30, shown in section. Said parts are arranged in three groups, separated by brackets or uprights 47, 48. In Fig. 1, the same usual arrangement is shown in plan and it is seen that the keys mounted in the sections opposite to brackets or uprights 47, 48, have their rear parts offset so as to reach the proper actuating rods. It is obvious that in these conditions the transposition of the keyboard is impossible, inasmuch as the spacing of the keys in front of the piano does not correspond to the spacing of the piano actions in the rear. To render it possible to modify the piano having such or an analogous arrangement of the hammers, we provide simple equalizing devices which are to be used in substitution of actuating rods 46 and which we will now describe.

Referring to Fig. 8, in which parts 47, 48 are shown with their lower portion removed wippens 45 are actuated by actuating rods 49, which may be mounted on a longitudinal frame 50. The same are evenly distributed, their relative distance being equal to the width of the front part of keys 30, while wippens 45, as stated, are not evenly distributed. To equalize their distance therefore and to make these correspond to their relative actuating rods, we provide each hammer rod with a suitable attachment projecting therefrom and termi-

nating directly over the corresponding actuating rod 49. Said attachment is preferably composed, as illustrated in detail in Figs. 11, 12, 13, of a stud 51, which can be screwed to the wippen by means of its part 70 52 and provided with a hole in which can be adjustably inserted a stem 53 of a projecting member 54, which can be retained in position by means of a set screw 55. Said projecting member 54 is therefore adjustable 75 both angularly and radially, and by its use each wippen can be readily and easily made to correspond with the proper actuating rod 49. The same equalizing devices are used to render the operating ends of keys 30 80 equally distanced so as to correspond with the actuating rods in all the positions of the keyboard. To this end, at the rear of each key 30, we screw a stud 51 on which is mounted a projection member 54 so as to 85 terminate directly underneath the proper piano action actuating rod. The arrangement of these different parts is shown in detail in perspective view Fig. 11, while Fig. 9 is a plan view showing the relative position of the wippens, actuating rods and upper projecting members 54; and Fig. 10 is a plan view showing in detail the relative position of the actuating rods, of the rear ends 90 of the keys 30 and of the lower projecting members 54. 95

In Fig. 11 45 is the hammer rod, 49 the actuating rod for the same, and 30 is the corresponding key; 51 is the stud screwed at the rear end of key 30, and 54 are the projecting members mounted on said stud and at the lower end of rod 49.

From the foregoing it can be seen that we provide simple and efficient means whereby the transposition of the keyboard of a piano 105 having unevenly distributed hammers is rendered possible, the rear ends of the keys having their points of action on the actuating rods uniformly distanced according to the spacing of said actuating rods. The 110 compensation or equalization of distances between the various parts of the mechanism can also be effected by means of members projecting from the lower part of existing actuating rods, and members projecting from 115 the rear part of the keys; this however would necessitate the employment of devices to prevent the actuating rods from rotating on their axes so as to maintain an equal distance between the ends of the members projecting from the same. These and other details pertaining to our invention can be changed without substantially departing from the spirit of the same; and we reserve ourselves the right of bringing to our invention all such changes and modifications which enter fairly within the scope of the appended claims.

Having thus described and ascertained the nature of our invention, what we claim 120 125 130

as new and desire to secure by Letters Patent of the United States is:

1. In a piano the combination of a longitudinally shiftable keyboard, means for securing the same in its normal position, and means for mounting the same adapted to cause the automatic lowering of its rear end upon the said securing means being released. 5
2. In a piano the combination of a longitudinally shiftable keyboard, means for securing the same in its normal position, and means for pivotally mounting the same, adapted to cause the weight of its rear part to automatically lower the same upon the 10 said securing means being released.
3. In a piano the combination of a longitudinally shiftable keyboard, and means for clamping the same in and for releasing the same from its normal position, said means being adapted to be used by the operator to perform the shifting of said keyboard. 15
4. In a piano the combination of a longitudinally shiftable keyboard, means for clamping the same in and for releasing the same from its normal position, said means being adapted to be used by the operator to also perform the shifting of the same, and means for mounting the same adapted to cause the automatic lowering of its rear end 20 upon the said clamping means being released. 25
5. In a piano the combination of a frame, a keyboard pivotally mounted thereon and longitudinally shiftable, positioning means for the same, and clamping means adapted to be used by the operator to perform the shifting of the same when released from its 30 normal position. 35
6. In a piano the combination of a frame, a keyboard pivotally mounted thereon and longitudinally shiftable, and cam-acting clamps having means for manually operating the same, adapted to be used by the operator to shift said keyboard and to secure the same in its normal position. 40
7. In a piano the combination of a frame, a keyboard pivotally mounted thereon and longitudinally shiftable, positioning means for the same, cam-acting clamps having 45 means for manually operating the same adapted to be used by the operator to shift said keyboard and to secure the same in its normal position, and means for pivotally mounting said keyboard adapted to cause the weight of its rear part to automatically lower the same upon the said clamps being released. 50
8. In a piano the combination of a longitudinally shiftable keyboard having a plurality of keys unevenly distributed at their rear end, a plurality of unevenly distributed wippens, a plurality of uniformly distributed actuating means for said wippens, means 55 for causing said actuating means to operate the corresponding wippens, and means for 60 causing the rear end of said keys to operate said relative actuating means; substantially as set forth. 65
9. In a piano, a plurality of unevenly distributed piano action units mounted therein, a longitudinally shiftable keyboard comprising a plurality of keys unevenly distributed at their rear end, uniformly distributed actuating means for said action units, and means for causing said actuating means to operate the respective action units and to be operated by said keys. 70
10. In a piano, a plurality of unevenly distributed piano action units mounted therein, a plurality of uniformly distributed actuating means for said action units, a longitudinally shiftable keyboard, having keys operating said actuating means, and means for causing said actuating means to operate said action units; substantially as 75 set forth. 80
11. In a piano the combination of a longitudinally shiftable keyboard having a plurality of keys unevenly distributed at their rear end, a plurality of unevenly distributed wippens, uniformly distributed actuating rods for said wippens, members projecting from said wippens registering with said actuating rods, and members projecting from the rear end of said keys also registering with said actuating rods; substantially as 85 described and for the purposes as set forth. 90
12. In a device of the character described, in combination with a plurality of unevenly distributed wippens, and with a plurality of evenly distributed actuating means for the same, angularly and radially adjustable equalizing means mounted on said wippens causing the same to operate by the said actuating means. 100
13. In a device of the character described in combination with a plurality of evenly distributed wippen actuating means, and with a keyboard having the ends of the keys operating said actuating means unevenly distributed, angularly and radially adjustable equalizing means mounted on said keys causing the same to operate the said actuating means. 110
14. In a piano having a plurality of unevenly distributed piano action units mounted therein, a longitudinally shiftable keyboard, uniformly distributed actuating rods for said action units, members adjustably mounted on the wippens of said action units and projecting therefrom, having one end registering with said actuating rods, and members adjustably mounted on the keys of said keyboard also registering with said actuating rods; substantially as described and for the purposes as set forth. 120
15. In a device of the character described, the combination of a frame, a plurality of unevenly distributed piano action units 125

mounted therein, a longitudinally shiftable keyboard having keys unevenly distributed at their rear end, uniformly distributed actuating means for said action units, equalizing means causing the wippens of said action units to register with said actuating means, equalizing means causing the keys of said keyboard to also register with said actuating means, means for pivotally and shiftably mounting said keyboard, and means for clamping and operating the same.

5

16. A device of the character described comprising a frame, a plurality of unevenly distributed piano action units mounted therein, uniformly distributed actuating rods for said action units, members projecting from the wippens of said action units registering with said actuating rods, a key-

10

15

board pivotally mounted thereon and longitudinally shiftable on said frame and having keys unevenly distributed at their rear end, members projecting from the said keys registering with the said actuating rods, positioning means for said keyboard, means for clamping and operating the same, and means for pivotally mounting said keyboard adapted to cause its rear end to automatically drop upon the said clamping means being released; substantially as set forth.
